[57] ABSTRACT

Needle clamp for sewing machine, particularly child's sewing machine, with the needle clamp knob located between the parallel needle and presser bars. The clamp knob and screw extend from the needle bar to strike the presser bar when retracted from the sewing needle, thereby preventing loss of the clamp screw.

NEEDLE CLAMP FOR SEWING MACHINE**BACKGROUND OF THE INVENTION**

Needle clamps on sewing machine needle bars are generally located laterally projecting to the right in deference to a right-handed operator, or projecting to the front. Generally, the clamps used are small in size, there normally being no need to make them inordinately large for an adult operator. In fact, the presently used location of the needle clamp would increase the risk of harm to an operator by the rapid reciprocation of an enlarged needle clamp. In addition, an enlarged clamp would increase the reciprocating mass of the needle bar, requiring the expenditure of more energy and an increase in motor size and occasioning an increase in bearing wear.

However, for a few individuals, particularly children or those afflicted with arthritis, a larger needle clamp would be of considerable aid. In addition, a location of the needle clamp out of the usual area of operator manipulation is desirable to obviate accidental injury. Also a design which would eliminate the possibility of inadvertently totally unscrewing the needle clamp would be particularly desirable.

SUMMARY OF THE INVENTION

The above desired ends have been achieved in the invention where an enlarged diameter needle clamp knob is located between the needle bar and a presser bar situated parallel to the needle bar. The clamp screw emanating from the knob is of sufficient length to be threadedly retained in the needle bar when the clamp knob is backed against the presser bar. The clamp knob is advantageously made of synthetic plastic resin to permit the knob, though of relatively large physical dimensions, to maintain a small reciprocating mass.

BRIEF DESCRIPTION OF THE DRAWINGS

In the drawings:

FIG. 1 is a front elevation of a portion of a head end of a sewing machine with a needle bar carrying a needle clamp situated between the needle bar and a presser bar;

FIG. 2 is a front elevation of a portion of a needle bar carrying a needle clamp of the invention indicating the relative size;

FIG. 3 is a side elevation partially in section of a portion of the needle bar and a presser bar, with the needle clamp mounted on the needle bar, showing a sewing needle in the clamped position; and

FIG. 4 is a side elevation similar to FIG. 3 but with the needle clamp fully retracted and abutting the presser bar.

In FIG. 1 is shown a head portion 10 of a sewing machine, which head portion supports a presser bar 15 and needle bar 20. The presser bar 15 is supported in a fashion to urge a presser foot 17 towards a feed dog 18 beneath the presser foot. The needle bar 20 is supported for endwise reciprocation that a sewing needle 21 affixed to the needle bar by clamp 25 may cooperate with other sewing instrumentalities (not shown) of the sewing machine in the formation of sewing stitches.

The clamp 25 is formed with a knob 26, preferably

manufactured of relatively lightweight synthetic plastic resin and integrally molded with a clamp screw 27 of metallic material. The clamp knob 26 is formed with a diameter greater than twice that of the needle bar to insure that it may be readily manipulated (see FIG. 2). In FIG. 3 the clamp screw 27 is shown threaded into threaded hole 28 in the needle bar 20 and bearing against a flattened shank portion 22 of the sewing needle 21.

Referring to FIG. 4, it will be noted that the clamp knob 26 is of such a width and the clamp screw 27 of such a length as to prevent the complete withdrawal of the clamp screw from the threaded hole 28 in the needle bar 20. Once the needle clamp 25 has been inserted into the needle bar 20, prior to assembly of the presser bar 15 into the head portion 10 of the sewing machine, removal of the clamp can only be accomplished by disassembly of the sewing machine.

Thus an advantageous no-loss assembly has been created which may be readily manipulated while at the same time increasing operator safety by placing the needle clamp in a location not normally in the area of operator manipulation.

Having set forth the nature of this invention, what we claim is:

1. In a sewing machine having a needle bar with a longitudinal axis and a presser bar having a longitudinal axis parallel to the axis of said needle bar, a needle clamp carried on one extremity of said needle bar and adapted to accommodate a sewing needle therein, said needle clamp comprising means defining a needle accommodating seat at one extremity of said needle bar, means defining an aperture in said needle bar intersecting said needle accommodating seat, said aperture opening towards said presser bar, a screw thread means formed in said aperture, a clamp screw having knob means thereon, said clamp screw being threadedly received in said aperture, said clamp screw and knob means extending a length greater than the distance from said screw threaded aperture opening in said needle bar to said presser bar.

2. A needle clamp for a sewing machine having a circular needle bar adapted to accommodate a sewing needle in one end thereof and reciprocate along a reciprocating axis lengthwise thereof, a presser bar parallel to said needle bar, said presser bar being spaced from said needle bar, said needle clamp comprising a needle accommodating seat formed axially in one extremity of said needle bar, a screw threaded aperture formed perpendicular to the axis of said needle bar, said threaded aperture intersecting said needle accommodating seat and opening toward said presser bar; a clamp screw having knob means thereon threadedly received in said aperture said clamp screw and knob means extending a length greater than the distance from said screw thread opening to said presser bar.

3. A needle clamp as claimed in claim 2 wherein said knob means is formed of a synthetic plastic resin with a diameter greater than twice that of said needle bar, said knob means and said clamp screw being integrally molded together.
